Inventor

George J. Johnson,

By Charles Charles.

Attorney:

UNITED STATES PATENT OFFICE.

GEORGE J. JOHNSON, OF CROCKETT, TEXAS.

CURTAIN-FIXTURE.

No. 926,193.

Specification of Letters Patent.

Patented June 29, 1909.

Application filed December 19, 1908. Serial No. 468,362.

To all whom it may concern:

Be it known that I, GEORGE J. JOHNSON, a citizen of the United States, residing at Crockett, in the county of Houston, State of Texas, have invented certain new and useful 5 Improvements in Curtain-Fixtures; and I do hereby declare the following to be a full, clear, and exact description of the invention, such as will enable others skilled in the art 10 to which it appertains to make and use the same.

The invention relates to a curtain fixture and more particularly to the class of cable tighteners for drawing taut or making loose 15 cords or chains adapted to be actuated for raising and lowering a curtain shade.

The primary object of the invention is the provision of a curtain fixture for use in the manipulation of curtain shade rollers and 20 comprises a cord or chain tightener carrying a pulley over which is trained a chain or cord also trained over a pulley fixed to the curtain shade roller, the said tightener comprising an adjustable member whereby the cord or 25 chain can be drawn taut or made slack to permit the ready and easy manipulation of the curtain shade roller to raise or lower a curtain mounted thereon.

Another object of the invention is the provision of a curtain fixture comprising a cord or chain tightener for use with curtain shade rollers, the construction of which tightener is simple, it being capable of ready and quick 30 attachment to a window frame, efficient in 35 operation and inexpensive in the manufacture.

With these and other objects in view the invention for example consists in the construction, combination and arrangement of 40 parts as will be hereinafter more fully described and as illustrated in the accompanying drawings which disclose the preferred form of embodiment of the invention, while the novelty of the invention will be included 45 in the claims succeeding the description. However, it is to be understood that changes, variations and modifications may be made such as come properly within the scope of the 50 claims hereunto appended without departing from the spirit of the invention.

In the drawings: Figure 1 is a front elevation of a window frame, a curtain-shade roller mounted thereon and the invention applied to the window frame. Fig. 2 is a plan 55 view of the base plate of the curtain fixture with its other adjunct parts removed there-

from. Fig. 3 is a top plan view of a shell or casing partly in section and adapted to be mounted on the base plate. Fig. 4 is a perspective view of the removable end piece of 60 the shell or casing. Fig. 5 is a longitudinal sectional view of the curtain fixture. Fig. 6 is a side elevation of the adjustable or shiftable member carrying the pulley. Fig. 7 is a bottom plan view thereof. Fig. 8 is a transverse sectional view of the curtain fixture through the adjustable or shiftable member. 65

Similar reference characters indicate corresponding parts throughout the several views in the drawings.

In the drawings, the numeral 10 designates a window frame which may be of any well known construction and it being in this instance of the usual form, and mounted upon the same at opposite upper corners thereof 70 are shade brackets or hangers 11 in which is journaled a rotatable curtain shade roller 12 having fixed at one end thereof a grooved pulley 13 the groove of which is slightly roughened to prevent the slipping of the 75 cable or cord 14 trained thereover.

Near the lower end of one longitudinal side of the window frame 10 is mounted a cord or chain tightener comprising a base plate 15 the latter having at opposite ends recesses 16 80 and it is also formed on its upper face with a series of rack teeth 17 the same extending throughout the longitudinal extent of the plate. Removably fitted upon the base plate 15 is a shell or casing 18 having spaced 85 parallel side walls 19 formed with inwardly directed right angularly disposed guide flanges 20, the same forming therebetween a guide opening or slot 21 and united to the side walls 19 at one extremity of the casing is 90 an end wall 22 the latter having a right angularly disposed securing ear 23 the same having its base portion 24 offset and a portion thereof being correspondingly shaped to the recess 16 which latter accommodates a portion 95 of the said securing ear to permit the proper mounting of the casing 18 upon the base plate 15. The opposite end of the casing or shell 18 is fitted with a removable end wall 25 the latter having a right angularly 100 disposed securing ear 26 the base 24 of which is offset corresponding to the securing ear 23 and is adapted to fit in the recess 16 in the base plate 15, and which ears respectively are secured to the window frame 10 in any 105 suitable manner.

Within the casing 18 is adjustably mount-

ed a slide member 27 the latter having projecting from its lower face a plurality of spaced transversely disposed projections forming teeth 28 to engage the rack teeth on 5 the base plate 15 and which slide member is formed on its upper face with a longitudinal rib 29 which projects through the slot 21, the said rib forming at opposite sides thereof channels 30 frictionally engaging the guide 10 flanges 20 of the shell or casing. Mounted upon the rib 29 is a U-shape bracket 31 having journaled therein a grooved pulley 32 over which is trained the chain or cord 14 and which pulley is actuated by a thumb 15 piece 33 formed on its journal whereby through the medium of the chain or cord 14 the curtain roller 12 can be rotated for raising and lowering the curtain shade 34 mounted thereon. Projecting from the base 20 plate 15 are lugs 35 the latter arranged adjacent opposite sides of the rack teeth 17 so as to accommodate therebetween the side walls 19 of the shell or casing 18 so as to prevent any lateral displacement of the said side walls 25 of the shell or casing when the latter is mounted upon the base plate.

When it is desired to move the slide member 27 to make taut or slacken the cord or chain 14 it is only necessary to pull outwardly upon the slide member 27 so as to disengage its teeth 28 from engagement with the rack teeth 17 on the base plate 15 and in this manner the said slide member can be shifted longitudinally in the shell or casing 18 35 and upon the release of said slide member the same will lock against movement by the engagement of its teeth with the rack teeth 17 on the base plate and thereby maintain the chain or cord in a taut or slacked condition.

Threaded in the brackets 11 are thumb screw members 36 which latter serve to adjust the journals of the roller 12 so that in

event the said roller rotates too freely, the thumb screw members 36 will tighten the 45 said journals of the roller 12 with the brackets, to regulate its rotation.

What is claimed is—

1. A curtain fixture of the class described comprising a base plate containing recesses 50 in its opposite ends, a toothed rack formed on the upper face of said base plate, a removable casing having a guide slot longitudinally therein and adapted to be mounted upon the base plate, a securing ear formed on one end of said casing and adapted to fit in one of the recesses in the base plate, a removable end wall for said casing and having a securing ear adapted to fit into the other recess in the base plate, a slideable toothed member fitted 60 within said casing and guided by the longitudinal slot therein and adapted to engage the toothed rack, a bracket carried by the said member, and a grooved pulley journaled in said bracket and over which latter is 65 adapted to be trained a curtain shade cord.

2. The combination with a curtain shade roller, a pulley fixed thereto, and a cord trained over the latter, of a base plate having a toothed rack formed thereon, a removable 70 shell fitted upon said base plate and having a guide slot, a securing ear carried at one end of said shell and adapted to interfit said base plate, a slideable block having teeth to engage the toothed rack of the base plate and 75 shiftable in the shell, a pulley carried by said slideable block and adapted to actuate said cord, and a thumb member for actuating the last mentioned pulley.

In testimony whereof, I affix my signature, in presence of two witnesses.

GEORGE J. JOHNSON.
